CLAIM

The ornamental design for a soil moisture soil indicator, substantially as shown.

DESCRIPTION

FIG. 1 is a front elevational view of a soil moisture indicator showing our new design, the rear being a mirror image thereto;

FIG. 2 is a left side elevational view thereof;

FIG. 3 is a right side elevational view thereof;

FIG. 4 is a top plan view thereof; and

FIG. 5 is a bottom plan view thereof.

FIG 1

FIG 2

FIG 3
